UNITED STATES PATENT OFFICE

CARL STEINBERG, OF NEW YORK, N. Y.

HAT

Application filed July 26, 1930. Serial No. 470,848.

My present invention relates generally to hats and more particularly to hats manufactured from a braided material.

One of the objects of my invention is the production of a hat which combines selected characteristics of both the well known felt hat and the well known panama straw hat now in common use.

My invention generally involves the employment for hat manufacturing purposes of a braided material, the yarn of which is formed by spinning together filler threads which are fibrous and fluffy in character with stiffening threads which are of a woody type and which are relatively highly resilient.

From another aspect my invention relates to a hat made from such a braid and to which a felted characteristic is given by the fluffy component of the yarn employed in making the braid and to which is given the form retaining characteristic by a woody component of such yarn.

My invention further relates to the arrangement by which a braid of this character is spiralled continuously from the top of the crown to the extreme end of the brim and the successive spiral sections joined edge to edge so as to give a hat structure in which the lines along which the spiral sections contact are emphasized to give somewhat the appearance of a straw hat.

My invention generally relates to a hat combining the appearance and characteristics of both a felt and a straw hat.

For the attainment of these objects and such other objects as may hereinafter appear or be pointed out, I have illustrated one embodiment of my invention in the accompanying drawings, in which—

Fig. 1 is a perspective view of a hat embodying my invention;

Fig. 2 is an enlarged vertical fragmentary section taken on the line 2—2 of Fig. 1; and

Fig. 3 is an enlarged fragmentary view of a section of the hat with braided yarns partly unraveled.

Before proceeding to describe my invention, I will premise that in accordance with my invention, the hat is made from a flat braided material somewhat as is the conventional

straw hat and in Figure 3, I show in an enlarged way, two adjacent braid sections 10 and the manner in which they are united.

The braid of which two sections are represented in Figure 3, is made from a yarn 11 which is formed by spinning together a fibrous material 12 with strands of a woody material shown at 13.

The fibrous material 12 should be fluffy in character and should not be form retaining. Wool and cotton fiber are examples of the materials to serve this purpose. The woody strands 13 on the other hand are highly resilient and form retaining. They possess the characteristic that while they can be bent from the normal, they will normally return to their original form. They should furthermore be capable of being molded by pressure in the presence of steam in which event their normal will be that form to which it has been molded. Hemp is a good example of strands answering to the required characteristics of the strands which I have numbered 13. Horse-hair, jute, and the like also possess in a general way, the characteristics of the strands 13 requisite for the attainment of the purposes of my invention.

The yarn 11 spun of the materials 12 and 13 as above set forth is braided in any preferred or desired manner so as to produce a flat braid of the proper dimensions for the manufacture of any particular desired hat.

The hat in Figure 1 may be manufactured from the braid 10 by spiralling the braid flatwise beginning with what corresponds to the apex of the crown. In this operation the successive spiral sections are laid edge to edge as shown in Fig. 3 and are then joined edge to edge by an overthrow stitch as shown at 14 in this figure. The thread forming the seam 14 is preferably but not necessarily made of silk.

The blank is then finished off by being molded by pressure in the presence of steam to shape for example to that shown in Figure 1 and then is treated with a water proof filler.

Due to the components employed in making the yarn and the spinning together of these components, the braid made therefrom

will stretch considerably, but will always return to its normal length upon release. In addition, it is highly flexible and therefore easily workable, and will always return to its normal set position when permitted to do so. The fibrous component of the yarn will give to the hat made from braid formed of such yarn, the fluffy fibrous characteristic of a felt hat. The resilient woody component will tend to keep the hat in the shape into which it is molded and will permit the hat to readily return to that shape whenever the hat has been crushed or otherwise distorted.

Upon viewing Figure 3 of the drawing, it will be observed that the braid is loosely woven so that the hat of Figure 1 formed therefrom not only has little weight but permits also of the free circulation of air through the interstices resulting from the manner of formation of the braid of Figure 3. In this respect, it will have the characteristics of a straw hat. Furthermore, it will have the appearance of a straw hat because of the manner of its formation and this will be assisted considerably by the fact that the seam 14 will produce a ridge at the joints where the adjacent spiral sections contact so as to emphasize the fact that the hat is made of a braided material.

The presence of the fibrous component in the yarn of which this braid is made, will give to the hat the translucent and pellucid effect generally present in straw hats such as the type known as panamas. In fact, the hat possesses in appearance very many of the characteristics of this type of hat.

My experience with this hat indicates that in giving it the waterproof filler treatment, the hat can be made stiffer than is necessary because it seems to become more mellow and softer as it is subjected to climatic action. This I attribute to the presence in the hat of the fibrous component.

Having thus described my invention and illustrated its use, what I claim as new and desire to secure by Letters Patent is—

1. A hat comprising a crown and a brim and made of a flat braid, the braid being formed of a yarn composed of a fluffy fibrous material and a resilient woody material spun together, the resilient woody material being of a character that it will normally retain the form into which it has been set and to readily return to said setting when distorted therefrom, whereby a straw hat effect is produced the form of which is maintained by the resilient woody component of the yarn, and a felt hat effect will be produced by the fluffy fibrous component of the yarn.

2. A hat made of a braid, the yarn thereof being formed of a fluffy fibrous material and a resilient woody material, whereby the fluffy fibrous component gives a felted effect to the hat and the resilient woody material tends to keep the hat in the shape to which it has

been set, the yarn being loosely interlocked to form the braid so as to provide interstices whereby a free circulation and the hat has the pellucid, translucent characteristic of a panama hat.

In witness whereof I have hereunto signed my name this 25th day of July, 1930.

CARL STEINBERG.
